DESIGN FOR A COOKY

Walter O. Forrer, Milwaukee, Wis., assignor, by direct and mesne assignments, of one-half to Tip Top Cookies Inc., Ripon, Wis., a corporation of Wisconsin, and one-half to Kiddie Kookies Co., Fairwater, Wis., a corporation of Wisconsin

Application June 8, 1946, Serial No. 130,531

Term of patent 14 years

(Cl. D8—2)

To all whom it may concern:

Be it known that I, Walter O. Forrer, a citizen of the United States, residing at Milwaukee, in the county of Milwaukee and State of Wisconsin, have invented a new, original, and ornamental Design for a Cooky, of which the following is a specification, reference being had to the accompanying drawing, forming part thereof.

Fig. 1 is a plan view of the cooky showing my new design.

Fig. 2 is an edge view of the cooky.

Fig. 3 is a fragmentary cross section taken on line 3—3 of Fig. 1.

I claim:

The ornamental design for a cooky, as shown.
WALTER O. FORRER.
